OR D11,299

EX

No, 11,299

July 22, 1879

UNITED STATES PATENT OFFICE.

GEORGE S. BARKENTIN, OF HARTFORD, ASSIGNOR TO P. & F. CORBIN, OF NEW BRITAIN, CONNECTICUT.

DESIGN FOR DOOR HANDLE AND PLATE.

Specification forming part of Design No. **11,299**, dated July 22, 1879; application filed June 7, 1879.
[Term of patent 7 years.]

To all whom it may concern:

Be it known that I, GEORGE SLATER BARKENTIN, of the city of Hartford, in the county of Hartford and State of Connecticut, have originated and produced a new and original Design for Door Handle and Plate, of which the following is a full, clear, and correct description, reference being had to the accompanying engraving, making part of this specification.

The engraving sufficiently represents the shape and general outline of my design, in which—

A represents the plate, B the handle, and C the thumb-piece.

The ornamentation of the plate A consists of the square part *a*, having angular projections on its sides, and sunken panels inclosing raised-leaf ornaments on its four corners, within which are circular lines inclosing an eight-pointed star, at the center of which is a rosette. Between the points of the star are fan-shaped leaf ornaments, as shown. Abutting the square part *a* are the borders *b b*, formed of zigzag bands, each outer division of which incloses a fan-shaped leaf, and each inner division a sunken leaflet, extending from the borders *b b* longitudinally on each side of the plate; and transversely near the top are narrow sunken panels *c c c c e*, each panel inclosing a row of quarterfoils in relief, the upper panel being intersected by the raised part designed for the key-hole. The remaining surface of the plate is filled with the vertical flutes, as at *d d*, and terminating with the angular sunken panels *e e*, in which are leaf ornaments and rosettes in relief, as shown.

The handle B is ornamented with the borders *ff*, between which are the vertical flutes

g. On each arm of the handle are sunken panels inclosing quarterfoils in relief, as at *h*, between which are flutes, as at *i*.

The thumb-piece C has upon its upper surface a narrow sunken panel, *j*, following the line of its outer edge, within which is a row of quarterfoils surrounding a small leaf ornament, all in relief.

The handle-plate, as shown in the engraving, is designed to be used with a mortise lock and latch; but it will be readily seen that the same device can be adapted to a mortise or surface latch only by dispensing with the key-hole and shortening the plate without materially changing my design.

I claim as my invention—

1. The design of the shape and general outline of the plate A, handle B, and thumb-piece C, substantially as shown.

2. The design of the ornamentation upon the plate A, consisting of the square part *a*, the borders *b b*, the panels *c c c c e* and *e e*, and flutes *d d*, combined and arranged substantially as shown and described.

3. The design of the ornamentation upon the handle B, consisting of the borders *ff*, flutes *g g* and *i*, and panels *h h*, combined and arranged substantially as shown and described.

4. The design of the ornamentation upon the thumb-piece C, consisting of the leaf ornament surrounded by a narrow sunken panel, *j*, substantially as shown and described.

Signed by me this 4th day of June, A. D. 1879.

GEORGE SLATER BARKENTIN.
